UNITED STATES PATENT OFFICE.

HIRAM VIRGIL HENDRICKS, OF OKLAHOMA CITY, OKLAHOMA, ASSIGNOR OF ONE-HALF
TO GUY A. CROOKS, OF OKLAHOMA CITY, OKLAHOMA.

SAND SMOOTHING DEVICE FOR GOLF PLAYERS.

Application filed August 12, 1924. Serial No. 731,655.

To all whom it may concern:

Be it known that I, HIRAM VIRGIL HENDRICKS, a citizen of the United States, residing at Oklahoma City, in the county of Oklahoma and State of Oklahoma, have invented a new and useful Improvement in Sand Smoothing Devices for Golf Players, of which the following is a specification.

This invention relates to sand smoothing devices for use by golf players.

The object is to provide a device to be used principally by golf players for the purpose of smoothing the sand in the immediate locality of the ball, when the latter has stopped in such places, and to provide a level area free from inequalities, so that the golfer may fairly strike the ball in putting.

Another object is to provide such a device in a strong and durable form and of minimum weight, the said device acting on the sand in a manner to leave no ridges or depressions or marginal lines when manipulated in the same manner as an ordinary hoe, and being capable of being folded and readily placed and carried in a golf bag to occupy no more space therein than one of the golf clubs, the device being also easily and quickly adjusted for use by simple means and constructed in a manner and of material that will permit of its manufacture at a low cost.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures,

Figure 1 is a perspective view of the invention adjusted ready for use;

Figure 2 is a side elevation of the device in its folded position;

Figure 3 is a transverse section showing the manner of pivotally mounting the handle on the smoothing head.

Referring to the drawing there is shown a smoothing head 1, formed of a length of suitable hard wood, or other material, the length found to be of the most practical value being about fifteen inches. The head is round in cross section and of a uniform diameter throughout its length, the diameter being preferably about one inch, and the ends 2 of the same are rounded into hemispherical form having a diameter to merge into the parallel sides of the head, so that when the smoother is drawn across the sand there will be no line of demarkation as would be formed were the ends cut off square.

Intermediate of the ends of the head 1, there is initially provided a transverse slot 3, oblong in cross section and extending only partway through the smoothing head 1. Into this slot is adapted to be driven the shank 4 of an eye 5, formed integrally and preferably of brass so as to avoid rusting, the said shank being of a size and shape to correspond to the slot 3, or slightly larger than the same. On the flat sides of the shank there are provided a series of ridges or teeth 6, the outer faces of which are perpendicular to the axis of the shank to engage the wood and prevent the same from pulling out, while the other faces are inclined to facilitate the entrance of the shank in said slot. Other means may be used to supplement this.

A ferrule 7 preferably formed of brass, is bifurcated at one end to form spaced arms 8, each having an aperture 9, one of which is threaded, and said ferrule is pivotally connected to the aforesaid eye 5 by means of a thumb screw 10, having its shank traversing the apertures of the ferrule arms and the eye 5. The threaded end of the thumb screw shank engages the threads of the aperture 9, and a shoulder 11 of the thumb screw serves to bind the ferrule in any adjusted position within a semi-circle, when the said screw is turned to force the shoulder into contact.

The outer, free end of the ferrule is open, and the reduced end of an elongated handle 12 is adapted to be driven thereinto and held by a cross pin, or in any other desired manner. The length of the handle is such as to enable the operator to draw the smoothing head across the ground when grasping the handle at or near the end.

This relatively short handle enables the device to be readily placed in a golf bag along with the clubs, when the head is folded into the position shown in Figure 2, with the head arranged parallel with the handle and held by the thumb screw. When it is desired to use the device for smoothing the sand, it is only necessary to loosen the screw, turn the head to a position perpendicular to the handle and tighten again.

From the foregoing it will be seen that a simple, cheaply-manufactured, strong and durable device has been provided for the purpose of smoothing the ground for golfers, and one that may be quickly adjusted for use, or for placing within a golf bag or the like, and that the manner of attaching the handle to the head serves to prevent accidental separation of the parts.

20 What is claimed is:

1. A sand smoothing device for golf players' use, comprising a smoothing head round in cross section and of elongated form, a handle pivoted to the head intermediate of the ends of the latter, and means for binding the handle in any position relative to the head about the axis of its pivot.

2. A sand smoothing device for golf players' use, comprising an elongated wooden head of uniform diameter throughout its length and having its ends rounded, an elongated operating handle pivoted at one end to the center of the head, and means for binding the handle in a position perpendicular to the head or parallel thereto.

3. A sand smoothing device for golf players' use, comprising an elongated head

formed of wood of equal diameter throughout and having its ends formed semi-spherically, a metallic ferrule pivoted centrally to the head to swing in a semi-circle parallel thereto, means for holding the ferrule in any adjusted position, and a handle having one end secured in the ferrule.

4. A sand smoothing device for golf players' use, comprising a smoothing head formed of wood round in cross section and having its ends rounded, a pivot eye having a shank embedded in the head and extending transversely part way through the same and midway between the ends thereof, a ferrule having a bifurcated end to receive the eye, a handle secured in the ferrule, and a thumb screw for binding the ferrule and eye in different positions.

5. A sand smoothing device for golf players' use, comprising a smoothing head formed of wood round in cross section and having its ends rounded to merge therewith, said head having a centrally-located, transverse slot extending partway through the same, a shank adapted to be driven into the slot and having ribs or teeth to engage the wood and retain the shank, an eye formed in the exposed end of the shank, a ferrule having spaced arms at one end to straddle the eye, said arms having apertures one of which is threaded, a handle secured in the ferrule, and a thumb-screw for binding the arms to the eye in different positions.

In testimony that I claim the foregoing as my own, I have hereto affixed my signature.

HIRAM VIRGIL HENDRICKS.
